US0D1107924S

(12) **United States Design Patent** (10) **Patent No.:** **US D1,107,924 S**
(45) **Date of Patent:** **** Dec. 30, 2025**

(54) **WEARABLE BIOSENSING DEVICE**

(71) Applicant: **Empatica Srl**, Milan (IT)

(72) Inventors: **Parth Jariwala**, Brookline, MA (US);
Matteo Lai, Cambridge, MA (US);
Riccardo Sirtori, Milan (IT)

(73) Assignee: **Empatica Srl**, Milan (IT)

(**) Term: **15 Years**

(21) Appl. No.: **29/833,400**

(22) Filed: **Apr. 4, 2022**

(51) **LOC (15) Cl.** **24-02**

(52) **U.S. Cl.**

USPC **D24/186**; D11/3; D14/344

(57) **CLAIM**

The ornamental design for a wearable biosensing device, as shown and described.

DESCRIPTION

FIG. 1 is a perspective view of the wearable biosensing device;
FIG. 2 is a top view thereof;
FIG. 3 is a bottom view thereof;

FIG. 4 is a front side view thereof;

FIG. 5 is a back side view thereof;

FIG. 6 is a right side view thereof; and,

FIG. 7 is a left side view thereof.

The broken lines immediately adjacent the shaded areas represent the bounds of the claimed design while all other broken lines are directed to environment and are for illustrative purposes only; the broken lines form no part of the claimed design.

1 Claim, 7 Drawing Sheets
